UNITED STATES PATENT OFFICE

2,613,257

WIRE CREEPER

Edward Wollet, Lakewood, Ohio

Application June 3, 1950, Serial No. 165,909

3 Claims. (Cl. 175—376)

1

My invention relates to new and useful improvements in wire creepers.

The primary object of this invention is to provide a device that is adapted for stringing wires across a wide space after a first wire has been strung.

A further object of the invention is the provision of a device as described that is especially adapted for stringing wires to points or places that are inaccessible by other means, such as through trees or other interfering objects.

Another object of the invention is the providing of a device of the nature described that is simple in construction and operation.

The foregoing stated objects and others attainable in the use of the device will be readily observed from a reading of the description following, in conjunction with the accompanying drawings, in which:

Fig. 1 is a view of a segment of the pivoted blocks.

Fig. 2 is a vertical cross-sectional view of the device taken lengthwise.

Fig. 3 is a perspective view of the device.

Describing the invention as shown in the drawings: 1 is the body of the device with side plates 1A and 1B having an elongated frame-like form with the front end portion in a nose-like form and adapted to better pass through obstacles such as tree branches, etc. 3 is a guide rod fixed in the body of the device by means of a bolt 12 at the rear end and the front end fixed to a spacer block 2 by means of the bolt 3A. 4 is a front block pivotally mounted in the body by means of a point 4A and provided with a pulley sheave 7, in its lower end portion, 8 is a spiral spring fixed in the body by means of 13A and its forward end attached to the lower end of the block 6, pivoted on 6A, such block being attached to the under side of the (creeper) block 5 to which a wire to be strung is attached, the pivot 6A is supported by 11, the creeper traveler or 5 is supported movable on the guide rod 3 and is adapted to grip the strung wire 14, 13 is a stop for the creeper 5 and attached in the body 1 by means of 9B, 7 is a pulley sheave in the lower end portion of the pivoted block 6, the one end of the rope or cable 10 is fixed to the forward pivoted block 4, then passes over a pulley in the rear sheave 7 and the forward pulley in the sheave 7 in block 4, the length of such rope or pulley is determined by the length of the wire or wires to be strung by the device. 9 refers to the nose-like front end portion. 6B are bolts securing the side plates together to form the body 1. 15 as

2

shown in Figure 1 refers to the form of the upper end surface of the front and rear pivoted blocks as provided with a groove with means for gripping the under surface of the strung wire 14 to hold the "creeper" 5 in its advanced position on the wire 14 when the pull on the rope or cable 10 is released, 1C provides a means for fastening the rope 10.

The device may be constructed of any desired and suitable material, such as metal, or wood, or a combination of such materials, and of any desired size as its use may require.

In using, or operating the device, it is placed on a wire already strung 14, the wire to be strung is attached to the creeper 5 which is positioned in the rear part of the body of the device, having a rope, or cable 10 being attached to the forward pivoted block 4 and relayed to the pulley in the sheave in the rear block 6 and then doubled back to the pulley in the sheave in block 4 and its free length coiled beyond the rear end of the device. The creeper 5 is now pulled along on its supporting rod 3, with its lower surface contacting the wire 14, by means of the rope 10, which also carries the rear pivoted block 6 with it, i. e. with the creeper 5, to a forward position in the body adjacent to the block 4, and by releasing the pull on the rope, the spiral spring pulls the lower end of the rear block 6 backward so that its upper grooved surface comes into a gripping contact on the wire 14 thus holding the creeper in an advanced position, relative to wire 14, and at the same time the body moves forward to an advanced position on wire 14, which is determined by the stop 13 coming in contact with the rear end of the creeper in its gripped position on the wire 14. By again pulling on the rope, or cable 10 the creeper is released from the wire 14 and is advanced as before, such advance being determined by the length of the device, or the supporting rod 3.

By repeating the operation just described, the required number of times, the device is advanced to the predetermined location where the attached wire is to be fastened.

From the foregoing description and manner of operating and using the device, it will be readily understood that such device embodies new and novel features not found in present day devices used for similar purposes.

I have shown my device in a desired and useful form and structure for the purposes specified, however in adapting same for such purposes modifications in form, or arrangement in structure, or both, may be required without depart-

ing from the basic features of the invention or the scope of the appended claims.

What I claim is:

1. A wire creeper and stringer comprising in combination with a pre-strung wire, an elongated body of frame-like form, a traveler (or creeper) slidably mounted on and supported by a horizontal rod extending lengthwise of and supported in such body, the said traveler adapted to be propelled on the said pre-strung wire, a block pivotally supported underneath and in conjunction with the said traveler and having its upper end surface provided with means for contacting and gripping the said wire, a forward block pivotally supported in said body and derivatively in position beneath the said wire, a pulley sheave provided in each of the lower end portions of the said pivotally supported blocks, said pulleys adapted to receive a rope for operating the device, one end of said rope attached to the said forward pivotal block and the free end being passed around the said pulley in the said rear pivotal block, then forward around said pulley in said forward pivotal block, said free end then passes out through and beyond the rear end of the said body, a spiral spring having its one end attached to and within such body, and its opposite end secured to the lower end of the said rear pivotal block.

2. A wire creeper and stringer, comprising in combination with a pre-strung wire, the structure described in claim 1, the said traveler adapted to slide forward on said supporting rod to the forward end portion of same when a backward

pull is exerted on said rope and the said rear pivotal block likewise moving in the same direction and in conjunction with the said traveler, the said traveler and block held in such position on the said wire by the means on the upper end surface of the said rear pivoted block gripping the said wire by reason of the pull on the said rope ceasing and the said spring being activated.

3. A wire creeper and stringer comprising in combination with a pre-strung wire, the structure embodied in claim 2, the said body adapted to likewise advance, relative to said wire, a distance equal to the distance traveled by the said traveler and block, while the said traveler and blocks are being held in their said advanced position on the said strung wire, and the said travelers and block being released from their said forward held position by means of a pull on the said rope preparatory to their being again moved forward by a further pull on the said rope.

EDWARD WOLLET.
